HONING METHOD AND APPARATUS

Marsden C. Hutto, Detroit, Mich.

Application November 29, 1947, Serial No. 788,834

29 Claims. (Cl. 51—161)

1

This invention relates to a honing method and apparatus and more particularly to the honing of radially expansible circular articles such as piston rings.

Particularly with piston rings, it is desirable that they be accurately finished so as to engage continuously and accurately the wall of the surrounding cylinder while pressed against the cylinder wall by the resilience of the piston ring. Such finishing operations may be performed by moving the rings relative to honing surfaces engaging the peripheries of the rings. In order to impart such relative movement it has been the practice to so clamp the rings to the propelling mechanism that the rings are incapable of expanding during the honing thereof. The result is that the ring surfaces are not accurately finished to the exact shape or contour that they must have in order to fit tightly and continuously the walls of a cylinder when they are free to expand under their inherent resilience.

It is also desirable that the piston rings be honed to have a frusto-conical taper in order to provide maximum sealing effect between the piston and the surrounding cylinder and in order to have minimum contact with the cylinder wall.

It is also desirable that the honing of the piston ring proceed as rapidly as possible to the end that the piston rings can be individually honed thereby to avoid the necessity of assembling the piston rings in gangs preparatory to honing.

It is also desirable that with such individual honing of the piston rings the rings be capable of being rapidly inserted in the honing apparatus and rapidly removed therefrom so as to reduce the total time of the honing operation to a minimum.

It is accordingly one of the principal objects of the present invention to provide a honing method and apparatus in which the piston rings are rapidly honed to a contour which will continuously and accurately engage the wall of the cylinder in which the piston rings are fitted. Such contour is provided by supporting the rings during honing so that they are free to expand into engagement with a honing device which embraces the peripheral surface of the rings, whereby such peripheral surfaces are honed under substantially the same conditions of confinement and resilient expansible stress as obtained when the rings are subsequently used in a cylinder. Such rapidity of the honing is obtained by impressing fluid pressure internally against the piston rings so as to augment the expansive

2

pressure of the rings against the honing devices and thereby accelerate the honing action.

Another object of the invention is to provide such a method and apparatus in which the degree of internal fluid pressure so impressed upon the rings can be adjusted to suit the particular ring being honed.

Another object is to provide such a method and apparatus which hones the ring to provide an external frusto-conical taper thereby to provide a ring having the maximum sealing effect.

Another object is to provide such a method and apparatus in which the piston rings are honed individually thereby to avoid the time and labor spent in assembling the rings in gangs upon a suitable fixture and also to avoid the errors of misalignment and fit incident to such assembly.

Another object is to provide such a method and apparatus in which the rings are rapidly inserted into and removed from the honing apparatus so as to reduce the total time required for honing to a minimum.

Another object is to provide such a method and apparatus which will hone piston rings, some of which may have non-parallel end faces, so as to be of wedge form.

Another object is to provide an improved resilient reactance device in the form of an air cushion against which the piston ring being honed is worked.

Another object is to provide a piston ring honing apparatus which can be made as automatic as desired.

Another object is to provide such apparatus having braking means to bring the piston ring supporting parts rapidly to a standstill after each honing operation.

Another object is to provide such high speed honing apparatus which is of simple construction and which will stand up under conditions of severe and constant use without getting out of order or requiring repairs.

Other objects and advantages of the invention will appear from the following description and drawings in which:

Fig. 1 is a fragmentary vertical longitudinal section, partly in elevation, of honing apparatus embodying the present invention.

Fig. 2 is a fragmentary horizontal section taken on line 2—2, Fig. 1.

Fig. 3 is an enlarged fragmentary sectional view similar to Fig. 1 and showing the position of the parts with the piston ring about to enter the honing zone.

Fig. 4 is a further enlarged fragmentary sec-

tional view similar to Figs. 1 and 3 and showing the position of the parts with the piston ring being acted upon by the honing stones.

Fig. 5 is a fragmentary sectional view similar to Fig. 3 and showing the position of the parts with the honed piston ring leaving the honing stones preparatory to removal from the apparatus.

Fig. 6 is a fragmentary sectional view similar to Figs. 3 and 5 and showing the manner in which the parts of the honing apparatus separate to permit ready removal of the honed piston ring and the replacement of an un honed piston ring.

Figs. 7 and 8 are horizontal sections taken on the correspondingly numbered lines on Fig. 5.

Fig. 9 is an enlarged, fragmentary, vertical section taken on the line 9—9, Fig. 7.

Fig. 10 is a fragmentary sectional view similar to Fig. 3 and showing the position of the parts when the apparatus is in honing operation as shown in Fig. 4.

Fig. 11 is a fragmentary sectional view similar to Fig. 10 and showing the position of the parts when the piston ring is removed from the grinding zone as shown in Fig. 6.

Fig. 12 is a cross-section through a tapered piston ring ground in accordance with this invention.

The honing apparatus is shown as supported by a base which is shown as comprising a pair of spaced sheet metal standards 15 supporting a sheet metal top 16, the edges of which are flanged upwardly to retain any kerosene dropping thereon. This top supports a heavy metal plate 18 which forms the bed or base plate of the apparatus.

The piston ring 20 is reciprocated and rotated in contact with the honing stones and to effect such rotation an electric motor 21 is mounted on the base 22 of a pedestal 23 carried by the bed or base plate 18, this pedestal being formed to provide a horizontal hollow arm 24. In this arm is suitably journaled, as best shown in Fig. 2, a longitudinal horizontal shaft 25, a pulley 26 being fast to the rear end of this shaft and connected by a drive belt 28 with a pulley 29 fast to the shaft of the electric motor 21. A worm 30 is fast to the forward end of the shaft 25, this worm being housed within the outer or forward end of the arm 24 and meshing with a worm gear 31 which is journaled in the outer or forward end of the arm 24 to rotate about a vertical axis. For this purpose the lower end of the hub of this worm gear 31 is shown as journaled in a lower bearing 32 and on a supporting thrust bearing 33 carried by the lower wall of the hollow arm 24 and the upper end of the hub is shown as journaled in an upper bearing 34 carried by a supporting ring 35 mounted on the top wall of the hollow arm 24.

The worm wheel 31 is splined to a vertical shaft 36 so that this shaft is capable of vertical reciprocation in the hub of the worm gear 31 but is compelled to rotate therewith. To reciprocate this vertical shaft 36, a tubular post 38 is mounted on the supporting ring 35, this tubular post in turn supporting a hydraulic cylinder 39 in coaxial alignment above the shaft 36. A piston 40 is arranged in this hydraulic cylinder 39, the piston rod 41 of which extends downwardly through a gland or stuffing box 42 in the lower end of the hydraulic cylinder and which also extends upwardly through a gland or stuffing box 43 in the upper end of the hydraulic cylinder. Oil or other liquid is introduced into and exhausted

from the upper end of the hydraulic cylinder 39 through a line 44 and is introduced into and exhausted from the lower end of the hydraulic cylinder through a line 45. The lower end of the piston rod 41 extends through a ring 46 and has a collar 47 fastened to its lower end, a pair of radial and thrust bearings 48 and 49 being interposed one between the collar 47 and ring 46, and the other between the ring 46 and a bearing housing 50 between the sections of which the ring 46 is clamped. This bearing housing and its bearings provides a connection between the piston rod 41 and splined shaft 36 through which the shaft 36 is compelled to reciprocate vertically with the piston rod 41 but is free to rotate independently of this piston rod.

The lower end of the splined shaft 36 is formed to provide an annular outwardly extending flange or head 52 and a stub extension 53 projecting coaxially downwardly below this flange. This downward extension is internally formed to provide a hexagonal or out-of-round socket 54 and is externally provided with a bead 55 at its lower end. The flange 52 is also recessed on its underside to receive a rubber ring 56 which is preferably made of synthetic rubber such as neoprene to resist the effect of kerosene. A metal piston ring holding collar or plate 58 is held against the underside of the rubber ring 56 by an annular series of screws 59 extending upwardly into the flange 52 and the bore of this ring is fitted around the bead 55 at the lower end of the downward extension 53 of the splined shaft 36. The underside of this collar or plate is flat and disposed perpendicular to the axis of the shaft 36 so as to engage the upper face of the piston ring 20 during the honing operation. This collar or plate 58 is also provided below the downward extension 53 of the shaft 36, with a plurality of radial ducts 60 which extend therethrough for a purpose which will presently appear.

The bed or base plate 18 is apertured to receive a stationary vertical cylinder 65, this cylinder being arranged coaxial with the shaft 36 and having an outwardly projecting flange 66 which rests on the bed or base plate 18 and is secured thereto in any suitable manner as by the screws 68. An end head 69 is secured to the lower end of this cylinder 65 in any suitable manner, this end head being formed to provide a central tubular part 70 which forms a cylindrical bearing and slideway 71 for the lower end of a tubular shaft 72. The lower end 73 of this shaft is of reduced external diameter while the upper end 74 is of larger external diameter to provide a downwardly facing annular shoulder or step 75 near the center of the shaft. The extreme upper end of this shaft 72 is formed to provide an annular outwardly extending flange 76 and a stub extension 77 projecting coaxially upwardly above this flange and toward the downward stub extension 53 of the shaft 36. The flange 76 supports a metal collar or plate 78 which is fitted around the stub extension 77. The upper side of this collar or plate 78 is flat and disposed perpendicular to the axis of the shaft 72 so as to engage the under face of the piston ring 20 during the honing operation. This collar or plate is also provided, above the upward extension 77 of the shaft 72 with a plurality of radial ducts 79 which extend therethrough for a purpose which will presently appear.

The upper end of the bore 80 of the shaft 72 is threaded to receive the threaded base of a hexagonal or out-of-round neck 81 which projects

coaxially upwardly from the shaft 72 to interfit with the hexagonal or out-of-round socket 54 provided in the lower end of the shaft 36. This hexagonal neck 81 is provided with a vertical bore 82 extending part way up from the bottom of its base and a plurality of radial ducts 83 extend from the upper end of this bore 82 to the exterior of the hexagonal neck. Kerosene is forced through these radial ducts 83 into the chamber provided by the metal collars or plates 58, 78, piston ring 20 and shafts 36, 72 and for this purpose a kerosene pressure line 84 is connected with the lower end of the tubular part 70 of the cylinder end head 69, this kerosene pressure line 84 being in communication with these ducts 83 through the bores 71, 80 and 82 of the tubular part 70, shaft 72 and hexagonal neck 81, respectively.

The shaft 72 is non-rotatably but axially slidably fitted in a sleeve 85, the flange 76 at the upper end of the shaft 72 resting on the upper end of this sleeve. To provide such non-rotatable but axial slidable connection between the shaft 72 and sleeve 85, a pin 87 is secured in the sleeve 85 to project into a longitudinal groove in the shaft 72 as best shown in Fig. 3. The upper end 86 of the bore of this sleeve 85 is of enlarged diameter to fit the larger external diameter of the upper end of the shaft 72 while the lower end 88 of the bore of this sleeve 85 is of reduced diameter to fit the lower end 73 of reduced diameter of the shaft 72, an upwardly facing annular shoulder or step 89 being thereby provided in the bore of this sleeve 85 in opposing relation to the downwardly facing annular shoulder or step 75 of the shaft 72. An annular chamber 90 is thereby provided by the shaft 72 and sleeve 85 between these annular shoulders or steps 75, 89.

This chambered part of the shaft 72 and sleeve 85 is embraced by a stationary sleeve 91 which forms a bearing and slideway for the movable sleeve 85 and is supported by a horizontal partition 92 extending horizontally across the center of the stationary cylinder 65 and dividing it into an upper chamber 93 and a lower chamber 94.

Air under pressure is supplied to the lower chamber 94 through an air pressure line 95 connected with the lower end head 69 of the stationary cylinder 65. This air is supplied through the bottom wall of this chamber 94 so as to bubble up through the oil therein and pick up lubricant for subsequent deposit on the moving parts which this air passes. This air under pressure escapes through a port 96 when this port 96 is brought into register with an annular groove 98 in the exterior of the movable sleeve 85 around the chamber 90. This air under pressure passes from this groove 98 into the chamber 93 through a port 99 through the side wall of the movable sleeve 85 in line with the annular groove 98 and chamber 90. This air under pressure escapes from the annular chamber 90 into the vented chamber 93 when this annular chamber 90 is brought into communication with a port 100 through the wall of the movable sleeve 85 above its annular groove 98. The frictionally engaging surfaces of the stationary sleeve 91, movable sleeve 85 and shaft 82 can be lubricated through grease introduced from a grease fitting 101 through a radial grease duct 102 in the partition 92 into the annular groove 98 of the movable sleeve 85 and thence through the duct 99 into the annular chamber 90.

The upper end of the movable sleeve 85 is 75 frusto-conical taper 132 is provided on the pe-

formed to provide an outwardly extending brake flange 103, the upper surface of which is adapted to engage the under surface of a brake ring 104, the rim of which is secured over the otherwise open upper end of the stationary cylinder 65 by screws 105 or in any other suitable manner. The brake flange 103 of the movable sleeve 85 is vertically apertured, as indicated at 106, to permit kerosene to flow from the honing zone above, this kerosene thereby escaping into the upper chamber 93 of the stationary cylinder 65 and from which it escapes through a kerosene drain pipe 108. A cylindrical sheet metal guard 109 is secured to the underside of the brake flange 103 over the stationary sleeve 91 to protect the joint between the stationary sleeve 91 and its movable sleeve 85 from the kerosene.

An annular base 110 for the honing stones is secured, as by screws 111, to the rim 66 of the fixed cylinder, this base being in the form of a disk 112 having a bore fitting the periphery of the brake ring 104 and having an annular flange or rim 113 rising from its periphery. In this annular base is secured, as by screws 114, a ring 115, the upper side of this ring being radially grooved to provide a plurality of parallel sided slideways 116 in each of which a stone holder 118 is slidably fitted. Each stone holder is in the form of a metal block slidably fitted in its radial guideway and the several stone holders are retained in these guideways 116 by an annular cover plate 119 fitted on top of the radially grooved ring 115 within the rim 113 of the annular base 110 and secured by screws 121 extending into the grooved ring 115. This cover plate is provided with an annular flange 120 around its bore 122 and on this flange is secured, as by screws 123, the rim 124 of a piston ring receiver 125. The upper part 126 of the bore in this piston ring receiver 125 is of frusto-conical tapering form, the enlarged upper end of which is of greater diameter than the free piston ring 20 while the lower end thereof is of smaller diameter than the free piston ring 20 so that a piston ring placed in this tapered bore and moved downwardly is contracted and placed under stress. From the lower end of the tapering upper part 126 of the bore of the piston ring receiver, the piston rings 20 enter a cylindrical lower part 128 of this bore, this cylindrical lower part 128 of this bore being of the minimum diameter of the tapering frusto-conical upper part of the bore so that the piston rings 20 passing therethrough are held in a contracted or stressed condition.

On moving downwardly from the lower part 128 of the bore of the piston ring receiver 125, the piston rings encounter honing stones 130 made of abrasive particles bonded together and each secured to the forward end of the corresponding stone holder 118 in any suitable manner. The inner or working face 131 of each stone 130 conforms at its upper edge to the cylindrical lower part 128 of the bore in the piston ring receiver 125, these working faces being thereby in the form of segments of a circle. However, an important feature of the invention resides in the fact that the working faces 131 of the several honing stones are not cylindrical but are of tapering frusto-conical form as best shown in Fig. 4. Thus, the segmental working face 131 of each honing stone extends downwardly and inwardly to a smaller radius. In consequence, as the piston ring 20 is reciprocated vertically in contact with the working faces 131 of these stones, a

riphery of the piston ring. This taper is, of course, greatly exaggerated in the drawings, but is highly desirable in providing the maximum sealing effect between the cylinder and the piston carrying the piston rings and in providing minimum area of contact between the piston rings and the cylinder.

The honing stones are individually adjusted to proper radial position in any suitable manner. The means shown for this purpose comprise an adjusting screw 135 having an inner threaded end screwed into the threaded inner end of a bore 136 provided centrally in each stone holder 118 parallel its radial guideway 116. These radial adjusting screws 135 extend through the rim 113 of the annular base 110 and each is turned by means of a knob 138 at its outer end. Each of these knobs 138 is shown as screwed on the outer threaded end of its adjusting screw 135 and held against turning relative to the adjusting screw by a lock nut 139, as best shown at the right of Fig. 8. Each adjusting screw is held against radial movement relative to the rim 113 by the hub of its knob 138 and by an enlarged flange 140 fast to each adjusting screw and engaging the inside of the rim 113.

It is important that each stone holder 118 be tightly held in its guideway 116 so that it cannot chatter and interfere with proper honing of the piston ring. To this end each holder 118 is crowded to one side and toward the bottom of its guideway 116. To crowd each stone holder 118 toward one side of its guideway 116, a pointed screw 141 is carried by the cover plate 119 above a beveled recess 142 provided at the corresponding side edge of each stone holder 118. It will be seen, as best shown in Fig. 9, that screwing the several pointed screws 141 down forces the stone holders 118 laterally into firm engagement with the opposite side walls of the guideways 116. The stone holders are crowded against the bottoms of the guideways 116 by set screws 143 in the cover plate 119, each bearing downwardly on its stone holder, as best shown in Fig. 9.

The piston rings to be finished are usually marked on one end face to indicate that this face is to be the top of the piston ring when inserted into the cylinder. This is usually done by stamping "top" in this face of the piston ring. The piston ring to be finished in accordance with the present invention may be cylindrical or may be roughly tapered to frusto-conical form, in which latter event the face marked "top" would be the face at the small end of the taper.

In the operation of the piston ring honing apparatus, air under pressure of, say, 30 lbs., is supplied to the lower chamber 94 of the stationary cylinder 65 through the air pressure supply pipe 95, this air bubbling up through the usual body of oil in the bottom of this chamber so that the compressed air carries with it a small amount of lubricant. At the start of the operation the shaft 36 and its collar or plate 58 are elevated to the position shown in Fig. 6, in which position the upper collar or plate 58 is separated from the structure thereunder so that the operator is able to place the piston ring to be finished over the hexagonal stud 81 and into the upper frusto-conical part of the bore in the piston ring receiver 125. It is unnecessary that this ring be placed with precision, the ring assuming the position shown in Fig. 6 even though placed with little care. In so placing the piston ring, the operator places the ring top side down.

At this time the upper face of the lower piston

ring supporting collar or plate 78 is slightly below the upper extremity of this lower cylindrical part 128 in the bore of the piston ring receiver 125. This initial depressed positioning of this piston ring supporting plate or collar 78 is due to the fact that at this time the chamber 90 has been vented through the port 100. Accordingly, the air pressure in this chamber has been relieved so that the tubular shaft 72 and the lower piston ring supporting collar or plate 78 has dropped to a position where the upper face of the latter is slightly below the plane of juncture of the upper frusto-conical and lower cylindrical parts 126 and 128 of the bore in the piston ring receiver 125.

The operator then introduces oil under pressure into the upper end of the hydraulic cylinder 39 through the line 44 shown in Fig. 1, relieving, of course, a corresponding amount of oil from the line 45. This moves the piston 40 and piston rod 41 downwardly, thereby, through the bearings 48 and 49 contained within the bearing housing 50, to depress the shaft 36. This downward movement of the shaft 36 causes the upright hexagonal stud 81 on the tubular shaft 72 to enter the hexagonal recess 54 so that these two shafts are compelled to rotate in unison.

The continued downward movement of the splined shaft 36 causes its piston ring engaging collar or disk 58 to engage the now upper end face of the piston ring, this being, of course, the side opposite from that marked "top." This engagement of the piston ring causes the piston ring to be moved downwardly from the frusto-conical part 126 into the cylindrical part 128 of the bore in the holder 125 and into engagement with the opposing planar faces of the collars or plates 58, 78. If the end faces of the piston ring are out of parallelism, these collars or plates 58, 78 adapt themselves to this condition so that each collar or plate engages the full area of each end face of the piston ring. Thus, an important feature of the invention resides in the resilient backing for at least one of the collars or plates 58, 78 between which the piston ring is held, this resilient backing shown as comprising the ring 56 of synthetic rubber above the collar or plate 58. Because of this synthetic rubber ring 56, the collar or plate 58 is free to cock to a limited degree and hence conform itself to any reasonable out-of-parallel condition between the upper and lower faces of the piston ring. As the piston ring 20 is so moved downwardly through the diminishing lower end of the frustoconical part 126 of the bore in the holder 125, it is contracted radially inwardly. Accordingly, the piston ring 20 is held in a contracted condition in the cylindrical lower part 128 of this bore and tends to expand under its own inherent resilience. The continued downward movement of the splined shaft 36 causes the supporting collar or plate 78 to be depressed, this forcing downwardly the tubular shaft 72 and causing the upper flange 76 of this tubular shaft 72 to engage the upper end and depress the sleeve 85 and thereby release the brake flange 103 of this sleeve from engagement with the stationary brake ring 104, thereby to render the tubular shaft 72 and its sleeve 85 free to rotate, this shaft and sleeve being compelled to rotate in unison through the pin 87 projecting into the longitudinal keyway provided in the tubular shaft 72. At the same time, the piston ring 20 is brought into engagement with the frustoconical faces 131 of honing stones 130.

This downward movement of the sleeve 85 also brings its port 99 into register with the port 96 of its supporting stationary sleeve 91, this port 96 communicating with the air pressure chamber 94 of the stationary cylinder 65. Accordingly, air under pressure is admitted to the annular chamber 90 so as to bias the tubular shaft 72 upwardly. This upward biasing of the tubular shaft 72 is augmented by the air pressure acting against the lower end of the sleeve 85. The chambers 90 and 94, so containing air under the assumed pressure of 30 lbs., are therefore separate air cushioning devices which urge the lower piston ring supporting collar or plate 78 upwardly and which determine the pressure with which the piston ring 20 is held between the collars or plates 58 and 78.

The operator then starts the flow of kerosene through the line 84; starts the electric motor 21; and also alternately admits and exhausts oil to and from the lines 44 and 45 of the hydraulic cylinder 39 so as to reciprocate the piston 40 therein. This reciprocation of the piston 40 reciprocates the piston ring 20 vertically along the working faces 131 of the honing stones 130 preferably at a frequency in the order of 100 reciprocations per minute and with a stroke sufficient to carry the leading face of the piston ring 20 slightly beyond the upper and lower extremities of the honing stones 130. At the same time the piston ring is being rotated, preferably at a speed in the order of 115 R. P. M. by the electric motor 21, this rotation being provided through the belt drive 28, shaft 25, worm gear 30, worm wheel 31, to the shaft 36 on which the worm wheel 31 is splined and which is bearing downwardly upon the piston ring 20 as previously described.

In the reciprocation of the piston ring by the piston 40 within the hydraulic cylinder 39, the piston ring is biased upwardly by air pressure so that the reactance and holding pressure against the piston ring 20 is provided by an air cushion. Thus, during this reciprocation of the piston ring in contact with the honing stones, the air pressure, at the assumed value of 30 lbs., in the chamber 94 is impressed against the under side of the sleeve 85 and is also impressed against the shoulder 75 of the tubular shaft 72 since at this time the port 96 is in communication with the annular groove 98 on the sleeve 85 and hence establishes an air pressure within the annular chamber 90 equal to that within the air pressure chamber 94. This position of these parts is shown in Fig. 10 and the position of the other parts of the apparatus at this time is shown in Fig. 4.

The reactance or upward biasing of the tubular shaft 72 by this air pressure is sufficient to insure retention of the contact of the piston ring 20 with the two metal collars or plates 58 and 78 but is of such low value that this piston ring 20 held therebetween is free to breathe or expand under its own inherent resilience into contact with the working surfaces 131 of the honing stones 130. This insures that the peripheral surface of the piston ring is honed under substantially the same conditions of confinement and resilient stress as is obtained when the ring is subsequently used in a cylinder and insures against a wavy or snaky contour which would defeat the purpose for which the piston ring is intended to be used. At the same time, to expedite the abrasive action between the piston ring and the honing stones 130, this expanding

pressure of the piston ring is augmented by fluid pressure imposed within the ring, this fluid pressure adding to the inherent expansive pressure of the confined piston ring and increasing the pressure of the ring against the honing stones.

This fluid pressure is preferably provided by the use of kerosene or other cutting oil, which at the same time is played against the working surfaces 131 of the abrasive stones 130 so as to keep these working surfaces in optimum cutting condition. This kerosene is supplied under pressure from the line 84 and flows upwardly through the bore 80 of the tubular shaft 72 and into the bore 82 of the hexagonal stub 81. From this bore 82 the kerosene escapes through the radial ducts 83 into the annular chamber defined by the piston ring 20 and the collars or plates 58 and 78 between which the piston ring is held. The pressure of the kerosene in this chamber augments the inherent expansion pressure of the piston ring 20 in contact with the honing stones 130. At the same time a part of the kerosene from this chamber escapes through the radial ducts 68 and 79 extending through the collars or plates 58 and 78, respectively. The kerosene so escaping from these radial ducts is played against the working surfaces 131 of the honing stones 130 so as to wash these working surfaces and keep them in a clean and sharp cutting condition. It will be observed that the kerosene is played against these working faces 131 of the honing stones with considerable force. After being so used, the kerosene flows downwardly into the chamber 93 of the stationary cylinder 65 from which it is relieved by the kerosene drain line at 108.

It will be observed that these working faces 131 of the honing stones are not of cylindrical form but are jointly of frusto-conical tapering form so that the piston ring 20 is reciprocated alternately along the enlarging and contracting faces of these stones. This causes the piston ring to be honed with the beveled or frusto-conical taper 132, best shown in Fig. 12. This tapering form of the piston ring is of prime importance in providing the maximum sealing effect between the piston and the cylinder wall, a minimum area of contact being obtained between the piston ring and the cylinder wall, and oil pumping, with the ring properly positioned and properly fitting the cylinder wall, being positively avoided. This frusto-conical taper of the piston ring 20 and the working faces 131 of the honing stones is illustrated in exaggerated form, this taper of the piston ring being in the order of .005 inch for the average sized piston ring.

After the ring 20 has been sufficiently honed, the operator admits fluid under pressure to the line 45 of the hydraulic cylinder 39 so as to move the piston 40 upwardly; cuts off the flow of kerosene under pressure from the kerosene line 84; and de-energizes the electric motor 21. Raising the piston 40 raises the piston rod 41 and shaft 36, thereby to raise the enlarged head 52 and collar or plate 58 engaging the now upper end face of the honed piston ring 20, this being the end face opposite that marked "top". The air pressure within the lower chamber 94 of the fixed piston 65 and in the chamber 90 between the shaft 72 and sleeve 85 and acting on the under side of the sleeve 85 and shoulder 75 of the tubular rod 72, raises this sleeve and rod, thereby causing the lower collar or plate 78 and piston ring 20 to follow the shaft 36 in its upward movement. The brake flange 103 of the

sleeve 85 thereupon engages the brake ring 104 so as to stop rotation of this sleeve and the tubular shaft 72, this shaft and sleeve being pinned to rotate in unison by the pin 87. At this time the hexagonal stud 81 is in engagement with the hexagonal socket 54 so that the rotation of the shaft 36 and its motor drive is likewise subject to the braking action of the brake flange 103 against the brake ring 104, although it will be understood that a separate brake (not shown) can be provided for the shaft 36.

As the splined shaft 36 continues its upward movement the confined air pressure in the annular chamber 90 reacting against the shoulder 75 causes the tubular shaft 72 to continue to rise and follow the upward movement of the shaft 36. This movement continues until the parts reach the position shown in Fig. 5 at which time the screw 87 in the sleeve 85 reaches the bottom of its groove in the tubular shaft 72 so that further upward movement of the tubular shaft 72 is prevented and the splined shaft 36 and upper collar or plate 58 carried thereby, leave the piston ring 20. Following this, the socket 54 in the splined shaft 36 is withdrawn from the hexagonal projection 81 on the tubular shaft 72. As the sleeve 85 reaches the upper limit of its movement, the groove 98 of the shaft 72 registers with the vent port 100 of the sleeve 85, thereby venting the chamber 90 and permitting the shaft 72 and its collar or plate 78 to settle to the position slightly below the plane of juncture of the frustoconical and cylindrical parts 126 and 128 of the bore in the piston ring receiver 125. This dropping of the collar or plate 78 redeposits the piston ring 20 in the upper frustoconical part 126 of the bore in the holder 125 and from which it can be removed to be replaced with an un honed piston ring.

The parts are now in the position assumed at the start of the description of the operation and the cycle is repeated with a fresh un honed piston ring.

It will be understood that the operation of the apparatus can be made as automatic as may be desired so that the operator need only to press a start button to start the descending movement of the splined shaft 36, the other functions of the apparatus being automatically started and stopped in proper sequence to effect the described cycle of operations. Also, an electro-magnetic brake can be applied to the splined shaft 36 in circuit with the electric motor 21 and synchronized with the engagement of the brake flange 103 so that no strain is placed upon any of the parts. Such automatic control features are a matter of choice and design and as they are not inventive features they are not shown or described in detail.

As stone wear takes place, the honing stones 130 can be readily readjusted inwardly. For this purpose the operator loosens the set screws 144 and also loosens the pointed screws 141, this leaving the stone holders 118 free to slide radially along the radial guideways 116. The operator then turns the knobs 138 so as to adjust the holders 118 inwardly to the desired degree. Turning these knobs turns the screws 135 and since these screws are held against movement relative to the rim 113 of the base 110 and have threaded connection with the stone holders 118, the stone holders are advanced or retracted by turning the knobs 138.

When the desired adjustment of the stones 130 is achieved, the operator first tightens the sev-

eral pointed screws 141. The points of these screws bear against the faces of the inclined grooves 142 in the stone holders so as to crowd these stone holders clockwise as viewed in Fig. 8, and insure a firm fit against the corresponding sides of the grooves 116. The operator then screws down the set screws 114 which crowd the stone holders 118 against the bottoms of the grooves 116. The stone holders are thereby locked in these grooves and cannot chatter to interfere with the proper honing operation.

From the foregoing it will be seen that the present invention provides a very rapid method and apparatus for honing expansible piston rings through the application of internal fluid pressure to augment the inherent expansion of each piston ring against the stones of the surrounding abrasive device, while at the same time each piston ring being ground is free to breathe or expand under its inherent resilience so that it is honed under substantially the same conditions of confinement as are obtained when the ring is subsequently used in a cylinder, thereby to insure a ring having true circular contour and freedom from waviness and snakiness. At the same time the rings are ground so as to be of tapered or frusto-conical form. The apparatus is quickly loaded and unloaded by the simple expedient of placing the rings in the bore in the piston ring receiver and removing the finished piston rings therefrom. As a result of these features the individual honing of the piston rings in the practice of the present invention is much faster than securing a gang of piston rings in alternate relation with driver rings and honing the gang of rings as a group. Further, individual honing of the piston rings permits their being honed into the desired tapered form.

I claim:

1. The method of finishing a resiliently radially expansible circular article which comprises enclosing and gripping the opposite end faces of the article with a force sufficient to impart rotation thereto but insufficient to prevent radial expansion thereof, applying fluid under pressure to the interior of said enclosed article to expand said article and urge its peripheral surface against an embracing abrasive device, and drivingly producing relative movement between the article and the abrasive device through such gripping connection.

2. The method finishing a resiliently expansible circular article which comprises applying closure members to opposite end faces of said article with a force sufficient to impart rotation thereto but insufficient to prevent radial expansion thereof, applying fluid under pressure to the chamber provided by said article and closure members to expand said article and urge its peripheral surface against an embracing abrasive device, and drivingly producing relative movement between the article and the abrasive device through such gripping connection.

3. The method of finishing a resiliently radially expansible circular article which comprises permitting the article to expand within and yieldingly urge its peripheral surface against an embracing abrasive device, enclosing and gripping the opposite end faces of the article with a force sufficient to impart rotation thereto but insufficient to prevent radial expansion thereof, applying fluid under pressure to the interior of the enclosed article to augment the pressure of its peripheral surface against the abrasive device, and drivingly producing relative movement between

the article and the abrasive device through such gripping connection.

4. The method of finishing a resiliently radially expandible circular article which comprises enclosing and gripping the opposite end faces of the article with a force sufficient to impart rotation thereto but insufficient to prevent radial expansion thereof, applying cutting oil under pressure to the interior of said enclosed article to expand said article and urge its peripheral surface against an embracing abrasive device, drivingly producing relative movement between the article and the abrasive device through such gripping connection, and directing a part of the cutting oil under pressure against said abrasive device to keep it in a clean and sharp condition.

5. The method of finishing a resiliently expandible circular article which comprises applying closure members to opposite end faces of said article with a force sufficient to impart rotation thereto but insufficient to prevent radial expansion thereof, applying cutting oil under pressure to the chamber provided by the article and closure members to expand said article and urge its peripheral surface against the opposing working faces of an embracing abrasive device, drivingly producing relative movement between the article and the abrasive device through such gripping connection and relieving said cutting oil under pressure from said chamber against said working faces to keep them in a clean and sharp condition.

6. The method of finishing a resiliently radially expandible circular article which comprises arranging the working faces of an abrasive device in circular opposing relation and at an angle to the axis of the device, permitting the article to expand within and yieldingly urge its peripheral surface against said working faces of the abrasive device, gripping the end faces of the article with a force sufficient to impart rotation thereto but insufficient to prevent radial expansion thereof, and drivingly producing relative movement between the article and the abrasive device through such gripping connection to produce a frusto-conical bevel on the periphery of said article.

7. The method of finishing a resiliently radially expandible circular article which comprises arranging the working faces of an abrasive device in opposing circular relation and at an angle to the axis of the device, enclosing and gripping the opposite end faces of the article with a force sufficient to impart rotation thereto but insufficient to prevent radial expansion thereof, applying fluid under pressure to the interior of said enclosed article to expand said article and urge its peripheral surface against said working faces of the abrasive device, and drivingly producing relative movement between the article and the abrasive device through such gripping connection to produce a frusto-conical bevel on the periphery of said article.

8. The method of finishing a resiliently radially expandible circular article which comprises arranging the working faces of an abrasive device in opposing circular relation and at an angle to the axis of the device, enclosing and gripping the opposite end faces of the article with a force sufficient to impart rotation thereto but insufficient to prevent radial expansion thereof, applying cutting oil under pressure to the interior of said enclosed article to expand said article and urge its peripheral surface against said working faces of the abrasive device, drivingly producing

relative movement between the article and the abrasive device through such gripping connection to produce a frusto-conical bevel on the periphery of said article, and directing said cutting oil under pressure against said working faces to keep them in a clean and sharp condition.

9. The method of finishing a resiliently expandible piston ring having non-parallel, planar end faces, which comprises yieldingly applying the flat faces of closure members to the opposite non-parallel end faces of said piston ring with a force sufficient to impart rotation thereto but insufficient to prevent radial expansion thereof, introducing fluid under pressure into the chamber provided by said piston ring and closure members to expand said piston ring and urge its peripheral surface against an embracing abrasive device, and drivingly producing relative movement between the piston ring and the abrasive device through such gripping connection.

10. Apparatus for finishing resiliently expandible circular rings, comprising an abrasive device having its working faces in opposed circular relation, a plate adapted to engage each end face of said circular ring and hold said ring concentrically within said working faces, means for holding said plates against said end faces of said ring with a force sufficient to impart rotative movement to the ring, but insufficient to prevent radial expansion thereof into engagement with said working faces, means for moving said plates relative to said abrasive device to produce relative movement between said ring and working faces, one of said plates being provided with an opening therethrough leading to the chamber provided by said plates and ring, a fluid pressure supply line operatively connected with said opening and supplying fluid under pressure to said chamber to expand said ring and provide the desired contact pressure between said ring and working faces.

11. Apparatus for finishing resiliently expandible circular rings, comprising an abrasive device having its working faces in opposed circular relation, a pair of shafts concentric with said working faces and arranged in opposed relation to each other, a plate non-rotatably secured to each of said shafts at the end opposing the other shaft and adapted to engage the corresponding end face of said circular ring and hold said ring concentrically within said working faces, means biasing said shafts toward each other with a force sufficient to impart rotative movement from one of said shafts and its plates to the ring but insufficient to prevent radial expansion thereof into engagement with said working faces, means for rotating said one of said shafts relative to said abrasive device, and a fluid pressure supply line communicating with the chamber provided by said plates and ring and supplying fluid under pressure to expand said ring and provide the desired contact pressure between said ring and working faces.

12. Apparatus for finishing resiliently expandible circular rings, comprising an abrasive device having its working faces in opposed circular relation, a pair of shafts concentric with said working faces and arranged in opposed relation to each other, a plate non-rotatably secured to each of said shafts at the end opposing the other shaft and adapted to engage the corresponding end face of said circular ring and hold said ring concentrically within said working faces, means biasing said shafts toward each other with a force sufficient to impart rotative movement from

said shafts and plates to the ring but insufficient to prevent radial expansion thereof, means for rotating said shaft and plate assembly relative to said abrasive device, one of said shafts being provided with a bore communicating with the chamber provided by said plates and ring, and a fluid pressure line communicating with said bore and supplying fluid under pressure to said chamber to expand said ring and provide the desired contact pressure between said ring and working faces.

13. Apparatus for finishing resiliently expandible circular rings, comprising an abrasive device having its working faces in opposed circular relation, a pair of shafts concentric with said working faces and arranged in opposed relation to each other, a plate non-rotatably secured to each of said shafts at the end opposing the other shaft and adapted to engage the corresponding end face of said circular ring and hold said ring concentrically within said working faces, an out-of-round stud projecting from the end of one of said shafts and adapted to fit an out-of-round socket in the opposing end of the other of said shafts, means for moving said shafts axially toward each other with a force sufficient to impart rotative movement from said shafts and plates to the ring but insufficient to prevent radial expansion thereof, means for rotating said shafts and plate assembly relative to said abrasive device, said one of said shafts and its stud being provided with bores communicating with the chamber provided by said plates and ring, and a fluid pressure line communicating with said bores and supplying fluid under pressure to said chamber to expand said ring and provide the desired contact pressure between said ring and working faces.

14. Apparatus for finishing resiliently expandible circular rings, comprising an abrasive device having its working faces in opposed circular relation, a plate adapted to engage each end face of said circular ring and hold said ring concentrically within said working faces, means for holding said plates against said end faces of said ring with a force sufficient to impart rotative movement to the ring but insufficient to prevent radial expansion thereof, means for moving at least one of said plates relative to said abrasive device to produce relative movement between said ring and working faces, one of said plates being provided with an opening therethrough leading to the chamber provided by said plates and ring, a cutting oil pressure supply line operatively connected with said opening and supplying cutting oil under pressure to said chamber to expand said ring and provide the desired contact pressure between said ring and working faces, and means discharging said cutting oil under pressure against said working faces to keep said working faces in a clean and sharp condition.

15. Apparatus for finishing resiliently expandible circular rings, comprising an abrasive device having its working faces in opposed circular relation, a plate adapted to engage each end face of said circular ring and hold said ring concentrically within said working faces, means for holding said plates against said end faces of said ring with a force sufficient to impart rotative movement to the ring but insufficient to prevent radial expansion thereof, means for moving at least one of said plates relative to said abrasive device to produce relative movement between said ring and working faces, one of said plates being provided with an opening therethrough

5 leading to the chamber provided by said plates and ring, a cutting oil pressure supply line operatively connected with said opening and supplying cutting oil under pressure to said chamber to expand said ring and provide the desired contact pressure between said ring and working faces, and means discharging said cutting oil under pressure against the said working faces to keep said working faces in a clean and sharp condition, comprising a duct extending through at least one of said plates from said chamber toward said cutting faces.

16. Apparatus for finishing resiliently expandible circular rings, comprising an abrasive device having its working faces in opposed circular relation, a pair of shafts concentric with said working faces and arranged in opposed relation to each other, a plate non-rotatably secured to each of said shafts at the end opposing the other shaft and adapted to engage the corresponding end face of said circular ring and hold said ring concentrically within said working faces, means biasing said shafts toward each other with a force sufficient to impart rotative movement from said shafts and plates to the ring but insufficient to prevent radial expansion thereof, means for rotating said shaft and plate assembly relative to said abrasive device, one of said shafts being provided with a bore communicating with the chamber provided by said plates and ring, a cutting oil pressure line communicating with said bore and supplying cutting oil under pressure to said chamber to expand said ring and provide the desired contact pressure between said ring and working faces, and means discharging said cutting oil under pressure against said working faces to keep said working faces in a clean and sharp condition.

17. Apparatus for finishing resiliently expandible circular rings the end faces of which may be non-parallel, comprising an abrasive device having its working faces in opposed circular relation, a plate adapted to engage each face of said circular ring and hold said ring concentrically within said working faces, a support for each of said plates, a resilient member interposed between one of said supports and the corresponding plate and permitting said corresponding plate to cock and adapt itself to the non-parallel end face of said ring contacted thereby, means for biasing said plates toward each other with a force sufficient to impart rotative movement to the ring but insufficient to prevent radial expansion thereof, and means for moving the assembly of plate, ring and supports relative to said abrasive device to produce relative movement between said ring and working faces.

18. Apparatus for finishing resiliently expandible circular rings the end faces of which may be non-parallel, comprising an abrasive device having its working faces in opposed circular relation, a pair of shafts concentric with said working faces and arranged in opposed relation to each other, a rubber member non-rotatably secured 65 to the end of one of said shafts opposing the other shaft, a plate secured against said rubber member to permit said plate to cock relative to said shaft, a plate non-rotatably secured to the opposing end of the other of said shafts, said plates being adapted on axial movement of said shafts toward each other to engage the opposite end faces of said circular ring, means biasing said shafts toward each other with a force sufficient to impart rotative movement from one of said shafts and its plate to the ring but insuffi-

cient to prevent radial expansion thereof, and means for rotating said one of said shafts relative to said abrasive device.

19. Apparatus for finishing resiliently expansible circular rings, comprising an abrasive device having its working faces in opposed frusto-conical relation, means for holding said ring in said abrasive device with a force sufficient to impart rotative movement to the ring but insufficient to prevent radial expansion thereof into engagement with said working faces, and means for moving said holding means relative to said abrasive device to provide a frusto-conical taper on the periphery of said ring.

20. Apparatus for finishing resiliently expansible circular rings, comprising an abrasive device having its working faces in opposed frusto-conical relation, a plate adapted to engage each end face of said circular ring and hold said ring within said working faces, means for holding said plates against said end faces of said ring with a force sufficient to impart rotative movement to the ring but insufficient to prevent radial expansion thereof into engagement with said working faces, means for moving said plates relative to said abrasive device to produce relative movement between said ring and working faces and provide a frusto-conical taper on the periphery of said ring, one of said plates being provided with an opening therethrough leading to the chamber provided by said plates and ring, a fluid pressure supply line operatively connected with said opening and supplying fluid under pressure to said chamber to expand said ring and provide the desired contact pressure between said ring and working faces and means for rotating said shaft and plate assembly.

21. Apparatus for finishing resiliently expansible circular rings, comprising an abrasive device having its working faces in opposed circular relation, a plate adapted to engage each end face of said circular ring and hold said ring concentrically within said working faces, a device for reciprocating one of said plates lengthwise of the axis of said working faces, a cushion of compressed air biasing the other of said plates toward said one of said plates and holding said plates against said end faces of said ring with a force sufficient to impart rotative movement to the ring but insufficient to prevent radial expansion thereof into engagement with said working faces, and means for rotating said assembly of plates and ring.

22. Apparatus for finishing resiliently expansible circular rings, comprising an abrasive device having its working faces in opposed circular relation, a pair of shafts concentric with said working faces and arranged in opposed relation with each other, a plate non-rotatably secured to each of said shafts at the end opposing the other shaft and adapted to engage the corresponding end face of said circular ring and hold said ring concentrically within said working faces, a device for reciprocating one of said shafts, a compressed air cushioning device biasing the other of said shafts axially toward said one of said shafts and holding said plates against said end faces of said ring with a force sufficient to impart rotative movement to said ring but insufficient to prevent radial expansion thereof into engagement with said working faces, and means for rotating one of said shafts.

23. Apparatus for finishing resiliently expansible circular rings, comprising an abrasive device having its working faces in opposed circular rela-

tion, a pair of shafts concentric with said working faces and arranged in opposed relation with each other, a plate non-rotatably secured to each of said shafts at the end opposing the other shaft and adapted to engage the corresponding end face of said circular ring and hold said ring concentrically within said working faces, a device for reciprocating one of said shafts and moving said one of said shafts axially to an extreme position away from the other of said shafts to release said ring from between said plates, a compressed air cushioning device biasing the other of said shafts axially toward said one of said shafts and holding said plates against said end faces of said ring with a force sufficient to impart rotative movement to said ring but insufficient to prevent radial expansion thereof into engagement with said working faces, valve means connecting said air cushioning device with a source of air under pressure when said reciprocating device is reciprocating said one of said shafts, valve means exhausting said air cushioning device when said reciprocating device moves said one of said shafts to said extreme position, and means for rotating one of said shafts.

24. Apparatus for finishing resiliently expansible circular rings, comprising an abrasive device having its working faces in opposed circular relation, a pair of shafts concentric with said working faces and arranged in opposed relation with each other, a plate non-rotatably secured to each of said shafts at the end opposing the other shaft and adapted to engage the corresponding end face of said circular ring and hold said ring concentrically within said working faces, a device for reciprocating one of said shafts and moving said one of said shafts axially to an extreme position away from the other of said shafts to release said ring from between said plates, the other of said shafts being provided with a cylindrical end of reduced diameter remote from the abrasive device, a sleeve fitting around said other of said shafts and having its bore at one end of larger diameter to fit the enlarged diameter of the corresponding end of the other of said shafts and its bore at the other end of smaller diameter to fit the reduced diameter of said other of said shafts and forming an annular air cushion chamber between said other of said shafts and said sleeve, said sleeve being provided with a port extending through the wall of said sleeve and registering with said chamber when said reciprocating device is reciprocating said one of said shafts, an air pressure line operatively connected with said port to supply compressed air to said chamber and hold said plates against said end faces of said ring with a force sufficient to impart rotative movement to said ring but insufficient to prevent radial expansion thereof into engagement with said working faces, said sleeve being provided with an exhaust port extending through the wall of said sleeve and registering with said chamber when said reciprocating device moves said one of said shafts to said extreme position, and means for rotating one of said shafts.

25. Apparatus for finishing resiliently expansible circular rings, comprising an abrasive device having its working faces in opposed circular relation, a pair of shafts concentric with said working faces and arranged in opposed relation with each other, a sleeve around one of said shafts and rotating therewith but axially movable thereon, cooperating plates carried at the opposing ends of the other of said shafts and said sleeve and adapted to engage the opposite end faces of said

ring and hold said ring concentrically within said working faces, a device for reciprocating said other of said shafts, a compressed air cushioning device between said one of said shafts and said sleeve and biasing said one of said shafts axially toward said other of said shafts, a separate compressed air cushioning device biasing said sleeve toward said other of said shafts, said air cushioning devices holding said plates against said end faces of said ring with sufficient force to impart rotative movement to said ring but insufficient to prevent radial expansion thereof into engagement with said working faces, and means for rotating said shaft, sleeve and plate assembly.

26. Apparatus for finishing resiliently expandable circular rings, comprising an abrasive device having its working faces in opposed circular relation, a pair of shafts concentric with said working faces and arranged in opposed relation with each other, a sleeve around one of said shafts and rotating therewith but axially movable thereon, co-operating plates carried at the opposing ends of the other of said shafts and said sleeve and adapted to engage the opposite end faces of said ring and hold said ring concentrically within said working faces, a device for reciprocating said other of said shafts, a compressed air cushioning device between said one of said shafts and said sleeve and biasing said one of said shafts axially toward said other of said shafts, a separate compressed air cushioning device biasing said sleeve toward said other of said shafts, said air cushioning devices holding said plates against said end faces of said ring with sufficient force to impart rotative movement to said ring but insufficient to prevent radial expansion thereof into engagement with said working faces, means for supplying compressed air to said first air cushioning device from said second air cushioning device during the reciprocating movement of said ring in contact with said working faces, and means for venting said first air cushioning device when said ring is retracted axially by said shaft, sleeve and plate assembly from contact with said working faces, and means for rotating said shaft, sleeve and plate assembly.

27. Apparatus for finishing resiliently expandable circular rings, comprising an abrasive device having its working faces in opposed circular relation, a pair of shafts concentric with said working faces and arranged in opposed relation with each other, a sleeve around one of said shafts and rotating therewith but axially movable thereon, co-operating plates carried at the opposing ends of the other of said shafts and said sleeve and adapted to engage the opposite end faces of said ring and hold said ring concentrically within said working faces, a device for reciprocating said other of said shafts, a compressed air cushioning device between said one of said shafts and said sleeve and biasing said one of said shafts axially toward said other of said shafts, a separate compressed air cushioning device biasing said sleeve toward said other of said shafts, said air cushioning devices holding said plates against said end faces of said ring with sufficient force to impart rotative movement to said ring but insufficient to prevent radial expansion thereof into engagement with said working faces, a brake flange on said sleeve, a brake ring engaging with said brake flange when said ring is retracted axially by said

shaft, sleeve and plate assembly from contact with said working faces, and means for rotating said shaft, sleeve and plate assembly.

28. Apparatus for finishing resiliently expandable circular rings, comprising an abrasive device having its working faces in opposed relation about a vertical axis, a pair of vertical shafts coaxial with said axis and arranged in opposed relation with each other, a plate non-rotatably secured to each of said shafts at the end opposing the other shaft and adapted to engage the corresponding end face of said circular ring and hold said ring concentrically within said working faces, means axially reciprocating one of said shafts and adapted to separate said one of said shafts and its plate from contact with said ring, a cushioning device biasing the other of said shafts toward said one of said shafts during the reciprocation thereof with a force sufficient to impart rotative movement from either of said plates to said ring but insufficient to prevent radial expansion thereof, a stationary ring receiver arranged above said abrasive device and having a downwardly contracting frusto-conical bore concentric with and above said working faces and into which the rings to be honed are placed upon said plate of said other of said shafts to be engaged by said plate of said one of said shafts and acting to compress said ring when said plates move said ring into cooperative relation with said working faces, and means for rotating said shaft and plate assembly.

29. Apparatus for finishing resiliently expandable circular rings, comprising an abrasive device having its working faces in opposed relation about a vertical axis, a pair of vertical shafts coaxial with said axis and arranged in opposed relation with each other, a plate non-rotatably secured to each of said shafts at the end opposing the other shaft and adapted to engage the corresponding end face of said circular ring and hold said ring concentrically within said working faces, means axially reciprocating one of said shafts and adapted to separate said one of said shafts and its plate from contact with said ring, a compressed air cushioning device biasing the other of said shafts toward said one of said shafts during the reciprocation thereof with a force sufficient to impart rotative movement from either of said plates to said ring but insufficient to prevent radial expansion thereof, a stationary ring receiver arranged above said abrasive device and having a downwardly contracting frusto-conical bore concentric with and above said working faces and into which the rings to be honed are placed upon said plate of said other of said shafts to be engaged by said plate of said one of said shafts and acting to compress said ring when said plates move said ring into cooperative relation with said working faces, and means for rotating said shaft and plate assembly.
